PANEL CONSTRUCTION

Rudolph Obermayr, Astoria, N. Y.

Application July 27, 1939, Serial No. 286,746

9 Claims. (Cl. 189—34)

This invention relates in general to panel construction and more especially to a metal panel construction of superior rigidity adapted for many uses.

5 Various metal panel constructions are in extended use as doors, wall partitions, hospital cubicles, metal furniture, cabinets and the like. In the manufacture of such panel constructions, it is essential to have the metal sheets firmly held or locked together.

It is an object of my invention to provide a panel from two metal sheets firmly held together by their edges by a locking strip.

15 It is another object of my invention to provide a panel construction from two metal sheets firmly held together by a locking strip adapted to grip or lock the edges of said sheets at a plurality of points.

Still another object of my invention is to provide 20 a panel construction from metal strips having their edges shaped to engage or grip a locking strip at least at two points.

With these and other objects in view, which 25 may be incident to my improvements, the invention consists in the parts and combinations to be hereinafter set forth and claimed, with the understanding that the several necessary elements comprising my invention may be varied in construction, proportions and arrangement without departing from the spirit and scope of the 30 appended claims.

I have shown in the accompanying drawing, 35 means for putting my invention into practical effect without limiting the improvements in their useful application to the particular constructions, which for the purpose of explanation, have been made the subject of illustration.

In the drawing,

Figure 1 shows a perspective view of a completed panel embodying my invention.

Figure 2 is an enlarged sectional view of a portion of one end of the panel.

Referring now to the drawing, a metal panel 11 is formed by marginally flanged metal sheets 45 12 and 13. The metal sheets 12 and 13 are provided, respectively, with inwardly extending flanges 14 and 15 shaped to engage a molding or locking strip 16. It is preferred to make the flanges 14 and 15 integral with the metal sheets 50 which are originally stamped out in flat condition and thereafter bent at their edges to form the flanges.

The inwardly extending flanges 14 and 15 are shaped to be engaged by the locking strip 16 in 55 such a manner that the locking strip exerts a

double grip on each of the flanges and thus avoids lateral shifting of the metal sheets 12 and 13 when the panel unit is completed and installed. One advantageous manner of shaping each of the inwardly extending flanges is illustrated in Figure 2, although it will be understood that other shapes may be employed for accomplishing the same purpose of my invention.

As illustrated, each of the flanges 14 and 15 is bent at three points so as to provide three sections in each flange extending in three different directions. The first section of each flange is at a right angle, or at an approximate right angle, to the metal sheets 12 and 13 as indicated by the numeral 17. The next section extends outwardly from the section 17, as indicated by the numeral 18, and each flange extremity 19, which is the last of the three sections on each flange, extends inwardly at approximately a right angle to the section 18, to a point substantially in line 20 with the right angle section 17.

The molding or locking strip 16 is adapted to firmly engage or grip the inwardly extending flanges 14 and 15 at two points on each flange, and thus provide a rigid assembly. The strip 25 16, of which there are four in number, to cover the edges of the panel, have an arched or curved outer surface 20 and a pair of extensions adapted to resiliently engage the flanges 14 and 15. Each of the extensions is composed of three sections, 30 the first section 21 being formed by bending the metal inwardly and parallel to the curved surface 20. In forming the sections 21, which extend inwardly to contact each other or at most with a relatively small space between them, it is important 35 in order to secure the desired engaging or gripping action, to have at least that part of the section 21 contacting the section 18 parallel to the section 16, as shown in Figure 2.

The next sections 22 of the extensions project 40 away from the curved surface 20 and preferably form a triangular shaped space between the sections 22, the purpose of which will be later explained. The extremity section 23 of each extension is bent inwardly towards the curved surface 45 20 and is sloped in such a manner as to be parallel to the section 19 of the flanges 14 and 15. By arranging the sections 23 substantially parallel to the sections 19 another point wherein the locking strip engages or grips the flanges of the 50 metal strips is thus provided.

The molding or locking strip 16 is somewhat resilient to firmly hold the metal strips together under a resilient tension. I have shown the strips 16 as being narrower than the thickness 55

of the finished panels to enable the ends thereof to firmly seat themselves in the juncture between the sections 17 and 18. In this manner the resilient properties of the strip 16 enables it to firmly grip the flanges of the metal sheets. The space between the sections 22 provides a restricted area for inward movement of the extremity sections 23 to enable a firm grip on the sections 19 and at the same time brings the parallel sections 18 and 21 in firm engagement with each other.

It will thus be apparent that when the molding or locking strip 16 has been joined to the metal sheets 12 and 13 there is provided a double gripping or locking action between the strip and flanges. One of the grips is effected between the parallel sections 18 and 21 and the other between the parallel sections 19 and 23. In this manner the metal sheets are firmly locked together and the possibility of lateral shifting thereof is avoided.

While I have shown the molding strip 16 as being narrower than the panel, it will be understood that it may be of the same order of thickness as the panel. Moreover, while the sections 22 are shown as forming a triangular space between them, it is not essential that such a space be provided as the double grip locking arrangement can also be accomplished with these sections somewhat parallel to each other. The space between the metal strips may be filled with a suitable sound-deadening filling material 24, such as cardboard, fibre or the like.

While I have shown and described the preferred embodiment of my invention, I wish it to be understood that I do not confine myself to the precise details of construction herein set forth, by way of illustration, as it is apparent that many changes and variations may be made therein without departing from the spirit of the invention or extending the scope of the appended claims.

I claim:

1. A panel construction comprising a pair of metal sheets having inwardly extending flanges, each of said flanges having a section extending at substantially a right angle to each sheet, another section inclined outwardly from the first-mentioned section and a third section inclined inwardly from the second-mentioned section towards the center of the panel and means for interlocking in a tension grip the second- and third-mentioned sections of said flanges to hold said metal sheets together under tension.

2. A panel construction comprising a pair of metal sheets having inwardly extending flanges, each of said flanges having a section extending at substantially a right angle to each sheet, another section inclined outwardly from the first-mentioned section and a third section inclined inwardly from the second-mentioned section towards the center of the panel and a molding strip for holding said pair of sheets together under tension, said molding strip having a curved outer surface and two separate sections adapted to firmly engage in a tension grip the second- and third-mentioned sections of each of said flanges.

3. A panel construction comprising a pair of metal sheets having inwardly extending flanges,

each of said flanges having a section extending at substantially a right angle to each sheet, another section inclined outwardly from the first-mentioned section and a third section inclined inwardly from the second-mentioned section towards the center of the panel and a molding strip for holding said pair of sheets together, said molding strip having a curved outer surface, a section at each end bent substantially parallel to said curved surface, another section extending away from each of said parallel sections and a third section extending from each of said second- and third-mentioned sections toward said parallel sections, the first- and third-mentioned sections of said molding strip being adapted to firmly engage, respectively, the second- and third-mentioned sections of each of said flanges.

4. A metal construction comprising a pair of metal sheets having inwardly extending flanges, each of said flanges having two flat surfaces extending in different directions and means adapted to firmly press against each of the two flat surfaces on each of said flanges in a direction to hold said pair of sheets together under tension.

5. A metal panel construction comprising a pair of metal sheets having inwardly extending flanges, each of said flanges having two extending surfaces projecting in different directions and means adapted to firmly press against each of the two extended surfaces on each of said flanges in a direction to hold said pair of sheets together in a double grip under tension.

6. A panel construction comprising a pair of sheets having inwardly extending flanges, each of said flanges having at least two sections thereof providing substantially flat surfaces, and means having at least two substantially flat surfaces adapted to press against each of the two surfaces on said flanges in a direction to hold said pair of sheets together in a double grip under tension.

7. A panel construction comprising a pair of sheets having inwardly extending flanges, each of said flanges having sections thereof providing flat surfaces, and means having at least two points adapted to press against each of the two surfaces on each of said flanges in a direction to hold said pair of sheets together under tension.

8. A panel construction comprising a pair of metal sheets having inwardly extending flanges, each of said flanges having a section extending at substantially a right angle to each sheet, another section inclined outwardly from the first-mentioned section and a third section inclined inwardly from the second-mentioned section toward the center of the panel, and means having sections adapted to engage in a tension grip the second and third sections of said flanges to hold said pair of sheets together under tension.

9. A metal panel construction comprising a pair of metal sheets having inwardly extending flanges, each of said flanges having two extended surfaces projecting in different directions, and means having two extended surfaces adapted to press against each of the two surfaces of said flanges in a direction to hold said pair of sheets together in a double grip under tension.

RUDOLPH OBERMAYR. 70
